CLAIM

The ornamental design for a rotary tool, as shown and described.

DESCRIPTION

FIG. 1 is a perspective view of a rotary tool showing our new design;

FIG. 2 is a right side elevational view showing the design for the rotary tool of FIG. 1;

FIG. 3 is a left side elevational view showing the design for the rotary tool of FIG. 1;

FIG. 4 is a top elevational view showing the design for the rotary tool of FIG. 1;

FIG. 5 is a bottom elevational view showing the design for the rotary tool of FIG. 1;

FIG. 6 is a front elevational view showing the design for the rotary tool of FIG. 1; and,

FIG. 7 is a rear elevational view showing the design for the rotary tool of FIG. 1.

The broken line showing of portions of the rotary tool is included for illustrative purposes only and forms no part of the claimed design.
